GARMENT MARKER

Gerardo Rizzolo, East Orange, N. J.

Application June 18, 1948, Serial No. 33,852

4 Claims. (Cl. 33—9)

1

This invention relates to devices generally termed garment markers and employed by tailors, dress-makers, fitters and the like, as a measuring apparatus for locating the position for marking the bottom portion of a garment such as a dress, coat or the like, while the wearer or person being fitted, is standing in an upright position. The main purpose of this invention is to provide a compact, rigid, simple, and attractive garment marker, which may be employed with ready facility in marking lengths of garments. In one of its more specific aspects it is particularly useful in marking the length of garments of various thicknesses, such as skirts, dresses, cloth coats, fur coats, and the like.

This application is a continuance, in part, of my copending application 563,433, filed November 14, 1944, which is now abandoned. Other objects and advantages of the invention will be readily apparent from the following description and drawing wherein:

Fig. 1 is a front view of a device embodying my invention.

Fig. 2 is a side view of the device shown in Fig. 1.

Fig. 3 is a top plan view of the device shown in Fig. 1.

Fig. 4 is a cross sectional view taken on line 4—4 of Fig. 2.

Fig. 5 is a cross sectional view taken on line 5—5 of Fig. 2.

Fig. 6 is a cross sectional view taken on line 6—6 of Fig. 2.

Fig. 7 is a cross sectional view taken on line 7—7 of Fig. 2.

As shown in the drawing, the novel measuring device comprises a base 10 which may be composed of any desirable material such as wood, metal or the like. An elongated flat supporting standard 11 is integral with a relatively short flat plate 12 which is located on the upper face of said base 10 at the front end thereof. The plate 12 may be secured to the base 10 by welding, rivets, or any other convenient manner to maintain the standard 11 in rigid upright position and at an angle of 90° to the base 10. The standard 11 has an elongated guide and support slot 13 between the ends thereof. The upper part of the standard 11 is struck out to provide a pair of guide and retaining ears 14, the major portion of which are spaced outwardly from the rear face of the standard 11, and the free extremities of which are spaced from each other. Guided by the standard 11 and supported thereby is an elongated substantial U-shaped rigid

2

element 15. The width of the element 15 is approximately the same throughout most of its length.

The element 15 comprises a leg 16 the front face of which is calibrated in inches, a rear leg 18 whose length is greater than that of the front leg 16, and a cross piece having a pair of slots 17 through which the retaining and guide ears 14 may pass in assembly. The front leg 16 extends flatwise along the rear of standard 11 and is overlapped by the ears or flanges 14. The lower end of leg 16 has an opening therethrough accommodating a bolt 19 which extends therethrough and through the elongated slot 13 of the standard 11. The outer end of the bolt 19 carries a wing nut 20. Extending across the legs 16 and 18 and secured thereto, in any convenient manner, is a reinforcing and spacer rod 21.

A supporting plate 22 is pivotally mounted on axis 23 to the upper end of the front leg 16. The rear of the plate 22 has a struck out portion 24 depending at an angle therefrom and serving to maintain plate 22 parallel to base 10 by bearing against front leg 16 as shown in Fig. 2.

Mounted flat-wise on plate 22 is a plate 25 of generally rectangular shape. One end of plate 25 whose width is greater than that of rear leg 18 has a recess 26 therein. The length of said slot 26 is greater than the width of leg 18 and the depth of slot 26 is greater than thickness of leg 18. The plate 22 has an elongated central slot 27 therein. A bolt 28 extends through an opening in the plate 25 and through the slot 27. A nut 29 carrying a finger pin 30 makes threaded engagement with the threaded end of bolt 28.

The operation of the device is as follows: The movable frame 15 is located in its lowermost position with the cross piece thereof, resting on the base 10, and the device is ready for use. The height of the garment line from the floor is determined and the frame 15, is slid upwardly to proper position on the guide standard 11, with the nut 29, being in loosened condition, and with the pivoted plate 22, and associated parts being swung about pivot 23, to its outward position away from leg 18, so that there is an unobstructed space between the legs 16 and 18. Then the wing nut 20 is tightened to lock the frame to standard 11. The skirt is inserted in the space between the legs 16 and 18 and the pivoted assembly is swung over on axis 23, as shown in Fig. 2. With garments of thin material the recessed end of plate 25, is used and the finger pin 30, is pressed to turn nut 29, to lock

the guide 25 to support 22. As the assembly is swung around axes 23, the outer end of plate 23 engages the garment along the platform guide 25. Then the plate assembly is swung away from the garment, the entire device, or the wearer, is moved, the plate assembly is swung back and garment marked again. The guide plate 25, may be slid to any desired location so as to provide the requisite space between its free or marking end, and the leg 18. It also may be swung around to provide a straight edge with no recess and this end is used generally, in the marking of thick cloths or furs.

While this invention has been described in detail, it is not to be limited thereby, because the same is subject to various changes and modifications within its scope.

I claim:

1. A device of the class described comprising a base, a standard mounted on and extending vertically upwardly from the base, a generally U shaped frame slidable vertically along the standard, said frame comprising a front leg adjacent the standard and a rear leg spaced from and substantially parallel to the front leg, said rear leg being longer than and extending beyond the top level of said front leg, means for clamping the front leg to the standard to maintain the frame in preselected vertical position with respect to the standard, a marker support pivotally connected to said front leg about a horizontal axis at the upper end thereof, and means for maintaining the support in a substantially horizontal position intermediate the legs, said support being swingable upwardly only about its pivotal connection with said front leg, the length of said standard being less than the length of said rear leg and the length of said front leg.

2. A device of the class described comprising a base, a standard mounted on and extending vertically upwardly from the base, a frame slidable vertically along the standard, said frame comprising a front leg adjacent the standard and a rear leg spaced from the front leg, means for clamping the front leg to the standard to maintain the frame in preselected vertical position with respect to the standard, a marker support pivotally connected to said front leg about a horizontal axis, and means for maintaining the support in a substantially horizontal position intermediate the legs, said last mentioned means comprising a member carried by and extending below the support and bearing against the front leg, said support being swingable upwardly only about its pivotal connection with said front leg.

3. A device of the class described comprising a base, a standard mounted on and extending vertically upwardly from the base, a frame slidable vertically along the standard, said frame

comprising a front leg adjacent the standard and a rear leg spaced from the front leg, means for clamping the front leg to the standard to maintain the frame in preselected vertical position with respect to the standard, a marker support pivotally connected to said front leg about a horizontal axis, means for maintaining the support in a substantially horizontal position intermediate the legs, said support being swingable upwardly only about its pivotal connection with said front leg, a marker guide carried by the support, said guide being pivotal and slidable with respect to the support, and means for maintaining the guide in preselected position with respect to the support.

4. A device of the class described comprising a base, a standard mounted on and extending vertically upwardly from the base, said standard having an elongated vertical slot, a frame slidable vertically along the standard, said frame comprising a front leg adjacent the standard and a rear leg spaced from and substantially parallel to the front leg, means extending through the slot for clamping the front leg to the standard to maintain the frame in preselected vertical position with respect to the standard, a marker support pivotally connected to the front leg about a horizontal axis, means for maintaining the support in a substantially horizontal position intermediate the legs, said last mentioned means comprising a member carried by and extending below the support and bearing against the front leg, said support being swingable upwardly only about its pivotal connection with said front leg, a marker guide carried by the support, said guide being pivotal and slidable with respect to the support, and means for maintaining the guide in preselected position with respect to the support.
